Patented January 5, 1904.

UNITED STATES PATENT OFFICE.

CHARLES C. PENFOLD, OF BUFFALO, NEW YORK.

DESIGN FOR A BUCKLE-PLATE OR SIMILAR ARTICLE.

SPECIFICATION forming part of Design No. 36,725, dated January 5, 1904.

Application filed November 27, 1903. Serial No. 182,913. Term of patent 7 years.

To all whom it may concern:

Be it known that I, CHARLES C. PENFOLD, a citizen of the United States, residing at Buffalo, in the county of Erie and State of New York, have invented a new, original, and ornamental Design for a Buckle-Plate or Similar Article, of which the following is a specification, reference being had to the accompanying drawing, forming a part thereof.

10 The accompanying drawing represents a

face view of a buckle-plate embodying my design.

What I claim as new, and desire to secure by Letters Patent, is—

The ornamental design for a buckle-plate 15 or similar article, as herein shown.

CHARLES C. PENFOLD.
